COOLING BED

Erik W. Mikaelson, Easton, Pa., assignor to
Treadwell Engineering Company, Easton, Pa.,
a corporation of Pennsylvania

Application January 29, 1942, Serial No. 428,779

2 Claims. (Cl. 80—42)

The present invention relates to cooling beds and more particularly to cooling beds of the type commonly used in or around steel plants, for receiving freshly rolled and highly heated steel products and supporting such products during a cooling period. A cooling bed of the general type contemplated herein is usually positioned in the general vicinity of a rail or plate mill, or adjacent the discharge end of any mill from which products are discharged in highly heated condition and, in the usual case, comprises a plurality of supporting members disposed in a generally horizontal plane, the work-engaging surfaces of the supporting members being spaced with respect to each other so that each article of work passing over the bed is supported only at a plurality of spaced points, thus permitting cooling air to reach the undersurfaces of such article as well as the upper surfaces.

Likewise it is preferred to construct and support the article-supporting members in such manner that they may be operated to advance the work slowly over the surface of the cooling bed, the speed of movement being so regulated that a highly heated article received on the bed at one point is, when it reaches the discharge end of the bed, cooled to a sufficient degree to permit its immediate processing by other means. Naturally, the parts of the cooling bed which are directly engaged by the highly heated work pieces themselves become highly heated in the continued operation of the bed for any substantial length of time. Where the work-supporting members are of the movable type and mechanism must be provided for effecting the movement of such members it is to be desired that such operating mechanism be protected from excessive heating and it is the principal purpose of the present invention to provide a cooling bed in which the work-supporting members are movable, member actuating means being provided, and which bed is provided with heat shielding means continuously interposed between the work and the actuating means for the work-supporting members, thus preventing overheating of the actuating means and interference with its functioning.

The figure shows an elevation partly in section of the cooling bed.

The invention relates particularly to a cooling bed of the type in which the work-supporting elements are circular disk-like members, sets of such members being mounted upon spaced parallel shafts, respectively, and the series of parallel shafts in turn being supported in bearings mounted upon pedestals. In this instance each shaft

comprises not only means for actuating work-engaging members, but likewise constitutes means for supporting such members and hence it is highly desirable that the shaft upon which the members are mounted be shielded against excessive heat which might result in its distortion. In the accompanying drawing portion of one such shaft, forming part of a cooling bed which may include many shafts of this type, is illustrated in side elevation, the supporting pedestals, the work-supporting members, and the means for shielding the shaft from the heat and the work superposed upon such members, being shown in section.

The shaft just referred to is indicated at 10 in the drawings, is horizontally disposed, and may be as long as needed, means (not illustrated) being positioned adjacent one end of the shaft and operatively connected thereto for slowly revolving the shaft in one direction of rotation. At spaced intervals the shaft passes through bearings, indicated at 11 in the drawing, which bearings are supported upon the upper ends of pedestals 12, the base of each pedestal resting upon a suitable foundation. Encircling shaft 10 are a series of 20 work-supporting members 13, there being a plurality of such members between each pair of adjacent bearings 11 and each member preferably being formed as an annular disk with a cylindrical work-engaging surface 13' and a central hub 13² encircling shaft 10, the inner cylindrical surface of the hub engaging the shaft rather closely, but the hub being freely slidable longitudinally on the shaft at all times. The members 13 are rotatable with the shaft, however, being splined thereto. Each hub 13² is provided with two annular shoulders 13³ upon opposite sides thereof and upon the ends of these shoulders are seated the ends of the cylindrical heat-shielding members 14, the shoulders 13³ being concentric with the axis of shaft 10 and the heat-shielding members 14 being, therefore, supported in concentric relation to the shaft. The outer ends of the outermost members 14, however, are supported upon annular abutment members 15 and 16, respectively, abutment 15 being pinned to the shaft by a pin 17 and abutment 16 being slidably mounted upon the shaft and splined thereto, as are the hubs of the work-supporting members 13. That work-supporting member 13 which is positioned intermediate abutment 16 and the adjacent bearing 11, is shown to have an enlarged hub which is pinned to the shaft 10 by means of a pin 18 so as to rotate with the shaft. The pin 18, of course, holds this member against longitudinal movement on the shaft. Intermediate the en-

larged hub of the fixed member referred to and the slidable ring 16, is a helical spring 19, normally in compression and urging member 16 toward the right. Pressure exerted by this spring serves to maintain the ends of the heat shielding and spacing members 14 in close contact with the respective annular shoulders 13³ of the several hubs 13² of the work-supporting members, the entire column of alternating heat-shielding members and hubs being forced tightly against the right-hand abutment 15 which is pinned to the shaft 10.

A plate resting upon the work-supporting members 13, and other work-supporting members 13 which are not illustrated but which comprise portions of the cooling bed, is indicated at 20 in chain lines. This plate when received on the cooling bed may be assumed to be in a highly heated condition and, by radiation from its undersurface, a large amount of this heat escapes downwardly and would ordinarily be transmitted directly to and absorbed by the shaft 10. Because of the interpositioning of the heat-shielding elements 14, however, the shaft 10 is largely protected and becomes only slightly heated, never being heated to such an extent that it is caused to warp or become distorted. Naturally, the heat-shielding elements 14 will expand when the cooling bed is first placed in use and these elements first become heated and to permit this expansion the horizontal column of hubs and heat-shielding elements is rigidly confined only at one end, i. e., by the annular member 15, and is yieldably confined at the opposite end, by the resiliently supported annular member 16. When the use of the bed is discontinued likewise a very considerable contraction of these parts will occur and the spring 19 will expand, taking up any looseness or play which would otherwise be present. The heat-shielding members may be formed of suitable materials, metal if desired, or substances having less capacity to transmit heat, if thought to be necessary. Other forms of the invention may be readily devised, as will be apparent to

one skilled in the art, in adapting the same to cooling beds of various types and constructions and primarily intended for supporting articles other than plates.

Having thus described the invention, what is claimed as new and desired to be secured by Letters Patent is:

1. In a cooling bed or the like, in combination, a shaft mounted for rotation, a plurality of spaced annular work-supporting and advancing elements slidably and non-rotatably mounted on said shaft, a plurality of heat shielding and element spacing tubular members encircling the shaft, one such shield being interposed between each two elements with its ends mounted on such elements and its inner surface spaced from the surface of the shaft, and resilient means for exerting pressure axially of the shaft to maintain tight engagement between said elements and shields at all times.
2. In a cooling bed or the like, in combination, a shaft mounted for rotation, a plurality of spaced annular work-supporting and advancing elements slidably and non-rotatably mounted on said shaft, a plurality of heat shielding and element spacing tubular members encircling the shaft, one such shield being interposed between each two elements with its ends mounted on such elements and its inner surface spaced from the surface of the shaft, and means for exerting pressure axially of the shaft to maintain tight engagement between said elements and shields at all times, said means including an abutment secured to the shaft at one end of the series of elements and members, a sliding abutment adjacent thereto, one end of a heat shielding tube being supported on said abutment, an expansion spring interposed between said fixed and sliding abutments, and a third abutment, at the opposite end of the series of elements and members for limiting sliding movement thereof along the shaft under the influence of said spring.

ERIK W. MIKAELSON.
